United States Patent

Des. 236,989
Patented Sept. 30, 1975

236,989

SPEAKER CABINET

Howard E. Holman, Fort Worth, Tex., assignor to Matsushita Electric Industrial Co. Ltd., Kadoma, Osaka, Japan

Filed Nov. 19, 1973, Ser. No. 417,358

Term of patent 14 years

Int. Cl. D14—01

U.S. Cl. D26—14 G

FIG. 1 is a front elevation of a speaker cabinet showing my new design;

FIG. 2 is a side elevation thereof, the opposite side being a mirror image;

FIG. 3 is a top plan view thereof;

FIG. 4 is a rear elevation thereof;

FIG. 5 is a fragmentary cross section taken on line 5—5 of FIG. 1; and

FIG. 6 is a fragmentary cross section taken on line 6—6 of FIG. 1.

I claim:

The ornamental design for a speaker cabinet, as shown and described.
